Inventor:

Louis Roehm,

By Hammer & Hammer,
Atts.

UNITED STATES PATENT OFFICE.

LOUIS ROEHM, OF CHICAGO, ILLINOIS.

HANGER.

974,524.

Specification of Letters Patent.

Patented Nov. 1, 1910.

Application filed November 12, 1909. Serial No. 527,662.

To all whom it may concern:

Be it known that I, Louis ROEHM, a citizen of the United States of America, and a resident of Chicago, county of Cook, State 5 of Illinois, have invented certain new and useful Improvements in Hangers, of which the following is a specification.

The main objects of this invention are to provide an improved form of curtain fixture 10 for attachment to the side of a window-casing or door frame without the use of nails or screws, and to provide an improved form of hanger which may be constructed entirely of sheet metal and which may be 15 readily adjusted to suit the thickness of the part upon which it is mounted.

A specific construction for curtain pole 20 hangers embodying this invention is illustrated in the accompanying drawings, in which:

Figure 1 is a side elevation of the fixture attached to a window casing. Fig. 2 is a top plan view of the same, the window-casing being represented in section. Fig. 3 is a 25 section on the line A—A of Fig. 1. Fig. 4 is a detail illustrating the sheet metal strip used as the hanger or support for the curtain pole.

In the construction shown, a clamping element or ratchet-bar 1, consisting preferably 30 of sheet metal, with notches 2 in the top edge, engages with the edge of the window casing 3, or other supporting member, by means of a foot 4 slotted to form spaced 35 fingers or prongs 5 and 6. These may be sharpened at their ends to insure more ready entrance behind the window-casing. The slotted construction insures admission of the 40 foot behind the casing, even though a nail or some similar obstruction may there be present. The other member of the fixture may consist of a hanger or support 7 preferably stamped from sheet metal, and bent to the shape shown in Fig. 4. This hanger 45 may have a tongue 8, stamped up near the middle of the strip to serve either as a retaining spring for the poles carried by the hanger or as a support for a curtain rod of small diameter. The hanger has a convolution 9 near one end, forming a spring-base having a flat surface 10, for engagement 50 with the front of the window-casing or other supporting member. Near this spring-base is a wing or extension 11 having a slot 55 through which passes the ratchet-bar 1. At the other side of the hanger is a similar

wing 12, serviceable if the hanger is desired for use at the other side of the window. A second convolution 13 in the hanger forms a sort of bearing surface for the side of the 60 ratchet-bar, and tends to prevent sidewise tilting of the hanger on the bar.

When installing the curtain fixture on a window-casing, it is only necessary to push or drive the slotted foot 4 of the ratchet-bar 65 under the window-casing or other supporting member, and then slip the slotted wing of the hanger over the end of the bar and push the spring base 10 firmly against the front of the window-casing while simultaneously forcing the top part of the wing 11 down into a notch of the ratchet. The 70 spring-base locks the wing in position, and insures stability of the hanger.

When the pole or poles are in position in 75 the hanger, the weight of the poles and the supported curtains assist in keeping the wing in place on the ratchet-bar by pulling downward on the hanger and tending to produce movement about the lower edge of 80 the convolution 9 as a fulcrum. Any movement about this edge relieves somewhat the tension on the spring 10 and there is therefore no tendency toward weakening the 85 spring through the weight of the pole supported on the hanger.

Although but one specific embodiment of 90 this invention is herein shown and described, it will be understood that numerous details of the construction shown may be altered or omitted, within the scope of the following 95 claims, without departing from the spirit of this invention.

I claim:—

1. In a curtain fixture, the combination of 95 a ratchet-bar, and a hanger movable on said bar and having a spring-base for engagement with a window casing.

2. In a curtain fixture, the combination of 100 a ratchet-bar having a foot for engagement with the back of a supporting member, and a hanger engaging with said ratchet-bar, and having a spring-base normally pressing against the front of said supporting member.

3. In a curtain fixture, the combination of 105 a ratchet-bar having a slotted foot for engagement with the back surface of a supporting member, and a hanger having a wing engaging with said ratchet bar and also having a spring-base operative to hold 110 said hanger in position on said bar.

4. In a curtain fixture, the combination

with a hanger having a slotted wing and also having a flat base for engagement with a supporting member, of a ratchet-bar passing through said wing for engagement therewith to hold said hanger in position against said supporting member.

5. In a curtain fixture, the combination of a ratchet-bar and a sheet metal hanger bent in a plurality of convolutions one of which 10 forms a spring for engagement with the supporting member, and another of which forms a bearing surface for said ratchet-bar when in place at the side of said hanger and engaging therewith.

15 6. In a curtain fixture, the combination of a ratchet-bar having a slotted foot for engagement with the back of a supporting member, and a hanger adapted to press against the front of said supporting mem-

ber and having a wing engaging with said 20 ratchet-bar, said hanger having a convolution forming a spring for locking said wing and bar together, and also having a second convolution forming a bearing surface for the side of said ratchet-bar.

25 7. A hanger, comprising a base, a clamping element having a foot adapted to coact with said base for gripping an interposed supporting member, and an adjustable ratchet connection between said hanger and 30 element.

Signed at Chicago this 9th day of November 1909.

LOUIS ROEHM.
